UNITED STATES PATENT OFFICE.

EDWIN G. HATCH, OF HOBOKEN, NEW JERSEY.

INSULATOR-CLAMP.

1,210,470.

Specification of Letters Patent.

Patented Jan. 2, 1917.

Application filed January 19, 1915. Serial No. 3,030.

To all whom it may concern:

Be it known that I, EDWIN G. HATCH, a citizen of the United States, and a resident of Hoboken, county of Hudson, State of New Jersey, have invented certain new and useful Improvements in Insulator-Clamps, of which the following is a specification, accompanied by drawings.

This invention relates to insulator clamps 10 for clamping a conductor to an insulator, but more particularly to that general type of insulator clamp in which the conductor is supported on top of the insulator and the clamping means or members embrace or encircle the body of the insulator.

In the past, accidents have occurred, in which property has often been damaged and people have sometimes been killed, where electric wires have broken on high tension 20 line-crossings over railroad right of way or over telephone and telegraph lines. It is very desirable and in fact highly important, therefore, to make certain that high tension electric wires, especially at the crossings, are 25 fastened to the insulators which carry the wires, just as efficiently as possible. A double cross arm construction has been found to be highly efficient, and by this construction I mean the case in which several 30 insulators are used instead of one, each insulator being supported on its own cross arm of wood or steel, and clamping means being provided for fastening the conductor to both insulators. The advantage of this double 35 cross arm construction resides in the fact that should one insulator fail, the line will not fall down against the cross arm and be grounded, producing a bad short circuit condition. It is unlikely that all insulators 40 would fail at the same time and at any rate, a factor of safety, which is required, is by this means provided.

One of the objects of this invention is to produce a simple, yet a highly efficient 45 means of attaching the electric line or conductor to the several insulators. Devices to accomplish this object have been designed in the past and used to considerable extent. There are two general types of insulator 50 clamp, the first embodying a cap generally of iron as a part of the construction, which cap is cemented to the insulator head and the second type embodying insulator clamps which encircle the neck of the insulator, and 55 are secured thereto and provided with conductor gripping devices for directly hold-

ing the conductor. One of the objections to the first type of clamp has been found from experience to be that the iron caps very often work loose because of the difference 60 between the coefficients of expansion of metal and porcelain, so that extremes of temperature, as a rule, result in a cracking of the porcelain or cement, thus eventually loosening the cap and decreasing the efficiency 65 of the device. Certain other objections have been found to insulator clamps in general, which apply as well to the second type of clamp. These clamps are made of metal and although they may be so designed 70 that they will not clamp the insulator tightly, it is a fact that in practice they do clamp the insulator very tightly in many instances, because there is considerable variation 75 in the sizes of insulators, even of the same make and style. The reason for this is that insulators are made from molds and when the mold is new, an insulator of one size will be produced, but when the mold is old, a variation in the dimensions of the insulator will be apparent. The clamp should be designed for an average size of insulator, but the porcelain of which the insulators are made is very brittle and easily chipped, so that when the clamps do not come in contact 80 uniformly with the porcelain, strain is produced at certain points, which may cause cracking or chipping of the insulator, thus reducing its efficiency very materially, if not entirely ruining the insulator. To meet 85 these objections, I have designed a clamping set which aims at eliminating the strains on the insulator, first by reducing the amount of metal surface in contact with the insulator, and secondly, by the introduction of 90 an elastic or plastic material forming cushioning means between the metal member and the porcelain. This material may be of some elastic substance, like rubber, or a more or less plastic material, as lead, which will 95 readily adjust itself to variations in the contour of the insulator.

In different insulators, a variation often exists in the dimension or distance between the center line of the side groove which holds the clamps, and the bottom of the top groove of the insulator which holds the conductor, and to provide for this difference, I have designed an adjustable clamping arrangement in which suitable provision is 110 afforded for adjusting the conductor gripping devices or jaws relatively to the clamp-

ing members, so that allowance can be made for the variations referred to without straining the conductor. My improved insulator clamp can also be so adjusted that the conductor will be certain to rest on the top of the insulator which is meant to carry the weight. In an ordinary clamp, as heretofore constructed, it is not always possible to insure that the conductor will rest on the top of the insulator, because the clamp must be made large enough to accommodate the maximum dimension between the bottom of the top groove and the center line of the side groove. If the clamp were to be made smaller than this, the conductor would be pulled down into the clamping members, which would strain the line and produce a kink or bend in it, thus weakening the line. If, on the other hand, the clamping members carry the conductor too high, the weight of the conductor would not come on the insulator head and might cause damage by bending the clamps down and injuring the porcelain.

In accordance with my improvement, provision is also made for an adjustment in the dimension between the center lines or axes of the several insulators forming the clamping set, and in order to provide for this adjustment, I tie the clamps of the insulators together, as by means of adjustable tie rods or turn buckles or other suitable devices. The use of such adjustable tie rods enables the separate clamping members to be tightly bound together and I also provide suitable means for bracing the tie rods, so that the clamping set is restrained from twisting sidewise and will keep its shape and alinement.

Insulator clamps, as a rule, and sometimes cemented caps, have clamping members designed to fit only one size of conductor. I have provided means, however, whereby the clamping members will engage several different sizes of conductor without requiring a special design or part. In order to effect this result, I employ bushings or sleeves preferably of thin sheet metal, which are wrapped around the conductor at the insulator heads, as well as between the jaws of the clamps. The use of these bushings is not absolutely essential, although they protect the conductor from any possible abrasion and serve the further purpose at the insulators of protecting the line from any slight leaks which may occur through the insulator heads.

My construction of clamping set also serves to act as an arcing shield to protect the conductor on flash over. The conductor gripping devices may extend for a substantial distance beyond the insulators, if desired, and these features of construction are fully described hereafter.

Preferred means for carrying out the in-

vention are shown in the accompanying drawings, in which—

Figure 1 is a side elevation of a clamping set; Fig. 2 is a plan view partly in horizontal section and partly broken away; Fig. 3 is a side elevation of a modification; Fig. 4 is a plan view of Fig. 3 partly in horizontal section and partly broken away; Fig. 5 is a plan view of another modification partly in section and partly broken away; Fig. 6 is a detail transverse sectional view on the line 6—6 of Fig. 1 and Fig. 7 is a detail side elevation of an insulator partly broken away showing a modified form of clamp.

Referring to the drawings, A and B represent two insulators mounted on the cross arms C and D which are connected in the usual manner by the cross piece E. In the form of the invention shown in Figs. 1 and 2, the insulator clamps for each insulator are constructed alike, so that a description of one applies to the other. Each insulator is provided with a clamp, comprising the clamping member F and a suitable conductor gripping device comprising the members G and H. The conductor J is supported in the grooves K in the top of the insulators and the clamping members F embrace the insulators in the circumferential grooves L.

In the form of the invention shown in Figs. 1 and 2, the clamping members F are shown substantially in the form of semi-circles and only partially encircle the insulators. Between each clamping member F and the insulator is preferably provided a cushioning means O of elastic material or soft metal. As shown in this instance the clamping member F is provided with the lugs P and the gripping member G is pivoted on the bolt Q. The gripping member or jaw H is suitably secured to the member G as by means of the bolts R. The clamping members F are suitably tied together as by means of the tie rods S which may be provided with the screw threaded ends T engaging the lugs U on the clamping members, so that the tie rods may be adjusted and tightened as by means of the nuts V. In order to brace the clamping set transversely and keep it in alinement, projections W may be provided on the clamping members F bearing against the tie rods S, so that a rigid construction is afforded.

In order to provide for variations in height in different insulators between the bottom of the top groove K and the center line of the side groove L, I prefer to provide means for vertical adjustment of the bolt Q in the lugs P and a simple mode of effecting this adjustment is to construct the lugs with slots X in which the bolt Q lies. By this bolt and slot construction, the bolt or pivot pin may be adjusted longitudinally in the direction of the axis of the insulator.

The sleeve or bushing Y encircling the

conductor J is shown in detail in Fig. 6 as a split sleeve preferably of soft metal, which may be wrapped around the conductor and in this way conductors of different sizes may 5 be accommodated by the clamp. If the sleeve Y is omitted, provision is still afforded by the gripping members G and H for accommodating conductors of different dimensions, because as shown the curved 10 gripping portions Z of the members are of sufficient radial curvature to take both large and small conductors within certain limits.

In the modifications shown in Figs. 3 and 4, the construction of tie rods S and gripping devices G and H is the same as in Figs. 15 1 and 2, but the clamping members are divided and constructed in two portions F', which encircle the insulators and are clamped thereto as by means of the bolts α .

20 In Fig. 5 a construction similar to Figs. 3 and 4 is shown, except that the tie rods S' are provided with turn buckles S². The ends of the tie rods S' in this instance are provided with eyes T' secured over the lugs 25 U' as by means of the nuts U².

In Fig. 7 another modification is shown applicable to a slightly different form of insulator A' in which the distance between the bottom of the groove b in the top of the 30 insulator and the center line of the groove c in the side of the insulator is very short, so that difficulty would be experienced in fitting gripping devices like those shown in Fig. 1, for instance, to the conductor. In a 35 construction like that shown in Fig. 7, the lugs d of the clamping member e are preferably bent at an angle as shown, and provided with the slots f to take the bolt g forming the pivot pin for the gripping member h. The gripping member or jaw j is 40 suitably secured to the gripping member h as by means of the bolts k. By this construction the conductor gripping devices are supported from above and the conductor 45 may be adjusted to lie in the top groove of the insulator.

Copies of this patent may be obtained for five cents each, by addressing the "Commissioner of Patents, Washington, D. C."

I claim and desire to obtain by Letters Patent the following:

1. A clamping set for clamping a conductor to insulators, comprising two insulators, clamping means for each insulator, conductor gripping devices carried by the said clamping means, tie members connecting said clamping means, and means for adjusting said tie members in accordance with 55 the distance between the axes of said insulators.

2. A clamping set for clamping a conductor to insulators, comprising two insulators, clamping means for each insulator, 60 conductor gripping devices carried by said clamping means, tie members connecting said clamping means at each side, means for adjusting said tie members longitudinally to accommodate different distances 65 between the centers of the insulators, and means for preventing transverse twisting of the insulators and clamping means.

3. A clamping set for clamping a conductor to insulators, comprising two insulators arranged side by side, clamping means embracing each insulator, conductor gripping devices carried by the said clamping means, projections at each side of the clamping means, and adjustable tie rods connecting 75 the said projections at each side of the clamping means.

4. A clamping set for clamping a conductor to insulators, comprising two insulators arranged side by side, clamps partially 80 encircling the outside of each insulator, conductor gripping devices carried by said clamps, and adjustable tie rods connecting the sides of said clamps.

In testimony whereof I have signed this 85 specification in the presence of two subscribing witnesses.

EDWIN G. HATCH.
